HEDGE TRIMMER

Melvin H. Boldt, Glenview, Ill., assignor to G. W.
Murphy Industries, Inc., Houston, Tex.

Filed Nov. 19, 1970, Ser. No. 26,080

Term of patent 14 years

Int. Cl. D8—03, 05

U.S. Cl. D8—8

Fig. - 1

Fig. - 2

FIG. 1 is a left side elevational view of a hedge trimmer, showing my new design;

FIG. 2 is a perspective view of the hedge trimmer illustrated in FIG. 1;

FIG. 3 is a top plan view of the hedge trimmer illustrated in FIG. 1.

FIG. 4 is a front elevational view of the hedge trimmer illustrated in FIG. 1;

FIG. 5 is a rear elevational view of the hedge trimmer illustrated in FIG. 1; and

FIG. 6 is a bottom plan view of the hedge trimmer illustrated in FIG. 1.

The broken line showing of a blade is for illustrative purposes only.

I claim:

The ornamental design for a hedge trimmer, as shown and described.
